FIG. 1

FIG. 2

FIG. 3

FIG. 4

FIG. 5

FIG. 6

FIG. 1 is a front perspective view of a battery-operated light showing my new design;

FIG. 2 is a rear view;

FIG. 3 is a side elevation;

FIG. 4 is a view from below;

FIG. 5 is a sectional view looking in the direction of the arrows 5—5 in FIG. 3; and

FIG. 6 is an enlarged perspective view of the part circled in FIG. 5.

The faceting on the lens is partially shown in FIGS. 1, 3 and 4 for convenience of illustration, it being understood that the facet configuration disclosed in FIGS. 5 and 6 would normally appear through the transparent lens.

I claim:

The ornamental design for a battery-operated light, as shown and described.
